ABRADING MACHINE

Charles Johnson and Joseph O. Olsen, Rockford,
Ill., assignors to Mattison Machine Works,
Rockford, Ill., a corporation of Illinois

Application January 17, 1934, Serial No. 706,966

18 Claims. (Cl. 51—143)

The present invention relates to a new and improved machine adapted for removing scale or producing fine surfaces on work sheets and particularly on thin flexible sheets of metal.

5 Sheets of certain material such for example as thin sheets of stainless steel tend to buckle when subjected to heat, and hence are difficult to handle in the abrading or polishing of their surfaces. One of the primary objects of the present invention resides in the provision of a novel machine for surfacing a flexible sheet in which the sheet is presented to the abrading or polishing tool in a fully curved condition, so as to avoid objectionable buckling and to insure a straight or flat line of cutting engagement.

10 Another object is to provide a machine of the foregoing character in which the work sheet is curved convexly toward the finishing tool in order to obtain a relatively narrow cutting zone resulting in a smooth finish, and in which the curvature is gradual so that sheets of substantial thickness can be handled without setting up excessive internal strains.

15 Another object is to provide a new and improved work support which is inexpensive in construction, which will protect the sheet against objectionable heating, and which will present all points along the curved sheet at a uniform position relative to the finishing tool when passing through the line of cutting engagement.

20 A specific object resides in the provision of a novel drum and cable drive for the work support in which the direction of pull will approach the line of movement of the support as the cable is shortened.

25 The abrading or polishing elements may be carried on an endless abrasive belt running over a pressure roller adjacent the work sheet, and then over one or more idler rollers. Belts of this character are likely to be unequal in length along their opposite side edges, and, if so, have a tendency to creep along the rollers. This is particularly objectionable at high speeds. Another important object, therefore, is to provide novel means for adjusting the idler roller or rollers to tension the belt uniformly along its width and to counteract any tendency to creep so that the belt will run true and will not be dangerous to operate.

30 A further object resides in connecting the power drive for the abrasive or polishing belt directly to the pressure roller so as to avoid objectionable tension in the flights of the belt between the rollers.

35 Other detailed objects reside in the provision

of novel means for securing the work sheet to its support, means for adjusting the finishing tool relative to the support to adapt the machine for sheets of different thicknesses, and supporting means for the belt guiding rollers permitting the 5 rollers to be mounted, removed or substituted with ease and convenience.

Further objects and advantages will become apparent as the description proceeds.

In the accompanying drawings, Figure 1 is a 10 perspective view of a machine embodying the features of our invention.

Figs. 2, 3 and 4 are fragmentary diagrammatic elevational views on a reduced scale, illustrating the relation of the abrading and polishing tool 15 to the work in different positions of the work support.

Fig. 2^a is a fragmentary plan view of the cable drum shown in Figs. 2 to 5.

Fig. 5 is a plan view of the work support.

Fig. 6 is a fragmentary transverse sectional view through the work support and one of the supporting guides taken substantially along line 6—6 of Fig. 5.

Fig. 7 is a fragmentary side elevational view 25 illustrating the means for securing the work to the support.

Fig. 8 is a perspective view of the construction shown in Fig. 7.

Fig. 9 is a side elevational view on an enlarged 30 scale and partially in section of the tool support.

Fig. 10 is a fragmentary sectional view taken substantially along line 10—10 of Fig. 9 and illustrating the means for adjusting the tool support vertically and the means for driving the tool. 35

Fig. 11 is a fragmentary vertical sectional view of the tool support, and illustrating one idler roller and the means for adjusting same.

Fig. 12 is a fragmentary horizontal sectional view taken substantially along line 12—12 of 40 Fig. 11.

Fig. 13 is a fragmentary front elevational view of the construction shown in Fig. 11.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

Referring more particularly to the drawings, the machine constituting the exemplary embodied 55

ment of the invention generally comprises an elongated floor bed 15 with an upright column 16 at its rear side and substantially midway of its ends, and with two pedestals 17 and 18 located respectively at opposite sides of the column. Mounted for longitudinal reciprocation on the top of the bed 15 is a suitable work support 19, preferably in the form of an elongated table, on which the work piece to be finished is adapted to be secured. While the invention in its broad aspects is not limited in its use to the finishing of any particular kind or form of work, it is especially adapted for removing scale from or otherwise producing a smooth finished surface 10 on one side of thin flexible metal sheets, such for example as the stainless steel A. A tool head 20 is mounted for vertical adjustment on the front of the column 16 and in overhanging relation 15 across the work table 19, and supports a finishing tool B positioned to act on the upper surface of the work sheet A. The finishing tool B may be provided in various forms depending on the character and condition of the work. In some instances, a number of different tools may be used 20 successively on the same work piece. Thus, the tool B may be an abrasive wheel, a buffing wheel or a tampico wheel. In the present instance, the tool B is shown as an endless abrasive belt extending completely across the work sheet A and running over a pressure roller 21, by which it is held against the sheet, and over one or more vertically spaced rollers 22, 22a.

The work sheet A is of substantial area, and when made of stainless steel for example is subject to buckling, if laid flat, when exposed to the heat generated in the abrasive or polishing action. One of the primary features of the invention, therefore, resides in presenting the sheet 25 A in a longitudinally curved condition to the abrasive belt B. As a result, buckling of the sheet A is effectively reduced to the desired degree, and a straight transverse zone or line of contact with the belt B is insured. The upper surface of the sheet A is convex so that a narrow zone of abrasive contact, resulting in relatively short cutting marks or scratches and hence in a smooth finish, is obtained, and that the sheet need be anchored only at one end to the table 19. 30 Also, the sheet A is curved throughout its entire length, and hence is fixed in position on the table 19 and not flexed progressively from end to end as it passes the abrasive belt B, and has but a small degree of curvature. The foregoing 35 method permits sheets of any thickness that can be bent to be handled, avoids setting up excessive internal strains in the metal, and if a reversal of movement of the sheet is desired, necessitates only the reversal of one machine part, 40 namely, the table 19.

To present the sheet A in such curved condition to the belt B, the table 19 is formed on the top with a smooth longitudinally curved work mounting surface 23, and is moved in a curved 45 path on the bed 15 such that all points along the sheet A when passing through the transverse abrading zone C will be disposed in a predetermined vertical position in relation to the belt B. The relationship by reason of which the abrasive belt B takes the same depth of cut on the curved upper surface of the sheet A at all points along its length is illustrated in Figs. 2 to 4. Thus, the belt B is in engagement with an intermediate 50 portion of the sheet A in Fig. 2, with the right 55 end of the sheet in Fig. 3, and with the left end

of the sheet in Fig. 4. When the sheet A is relatively thin, a sub-sheet (not shown) of cheap material may be placed between the sheet and the table 19 to prevent areas of the latter which would otherwise be exposed from contacting with the belt B. 5

The table 19 is mounted on two parallel guide-ways 24 extending along opposite sides of the top of the bed 15. Since the table 19 is to be movable in a curved path, each of the ways 24 is preferably inverted V-shaped in transverse 10 form, and consists of two straight opposite end sections in end abutment at approximately the longitudinal center of the bed 15, and equally and gradually inclined downwardly toward the ends of the bed. Thus, the ways 24 are also generally 15 inverted V-shaped in longitudinal form. Side flanges 25 on the table 19 overhang the outer sides of the ways 24.

Preferably, the ways 24 are not formed integral with the bed 15, but are provided by securing two longitudinally aligned base castings 26 to the top of the bed along each side. The castings 26 are in abutment at their adjacent ends, and are tapered in height toward their outer ends which project substantially beyond the ends of the bed 15. The tops of the castings 26 are formed on opposite sides with plane longitudinal downwardly and outwardly inclined seating surfaces 27, and with upstanding flanges 28 along the outer longitudinal margins of the surfaces 30 (Fig. 6). Steel bearing plates 29 are mounted on the surfaces 27, and are secured in position against the flanges 28 by means of a plurality of clamp bolts 30 threaded into the castings 26 and engaging the upper inner edges of the plates. It 35 will be evident that the upper surfaces of the plates 29 constitute the ways 24, and that the latter are greater in length than the bed 15.

The table 19 is supported at each corner and at all intermediate points is located in freely spaced 40 relation thereto regardless of its position of reciprocation. Thus, the table 19 upon being reciprocated along the ways 24 will move in a curved path. The curvature of the path depends upon the relative inclination of the opposite end sections of the ways 24, and as herein shown is comparatively small. The means for supporting the table 19 comprises four housings 31 secured in pairs to opposite ends of the table, and opening 45 downwardly respectively over the sections of the ways 24. Each housing 31 is formed with two sets of spaced bearings 32. Two anti-friction rollers 33 in bearing engagement against the underlying steel plates 29 are journaled respectively in the bearings 32 with their axes relatively inclined at the same angle as that subtended between the plates. Suitable resilient wipers 34 may be mounted in the outer end of the housing 31 for sliding engagement with the upper surfaces of the ways 24. 55

Preferably, the table 19 is of a closed hollow box construction in which the interior is divided by a central transverse partition wall 35 (Fig. 5). A plurality of spaced parallel baffle walls 36 are formed at opposite sides of the partition wall 35, and project alternately from opposite sides of the table 19 partially across the interior to define two tortuous cooling passages 37. A suitable cooling medium, such for example as water, may be supplied to the inner ends of the passages 37 through a branched pipe 38 adapted to be connected to a source (not shown). The cooling medium may be discharged from the outer ends of the passages 37 through drain pipes 39. 70

Any suitable means may be provided for driv- 75

ing the table 19. In the present instance, this means comprises a drum 40 (Figs. 2 to 5) formed in its periphery with a helical groove 41, and mounted in the bed 15 for rotation with a central transverse shaft 42. Two cables 43 are wound in opposite directions along the groove 41, and are anchored at their adjacent ends to the center of the drum 40. The outer ends of the cables 43 are attached respectively to two brackets 44 secured to the opposite ends of the table 19, and projecting downwardly into the space between the ways 24. Upon rotation of the drum 40, one cable 43 will be wound up, and the other cable will be unwound a corresponding amount, to translate the table 19. Preferably, the brackets 44 are offset relative to the longitudinal center line of the table 19 so that the pull exerted by either cable 43 will approach the perpendicular to the drum 40 as the table nears the corresponding end position.

If the convolutions of the drum groove 41 are made of uniform diameter, it has been found that some slack develops in the unsupported end of the cable when the table is near one limit of its travel. Such slack, while being taken up on reversal of the table, produces objectionable jerking and jarring of the table. To take up this slack and maintain the cables taut in all positions of the table, the outermost convolutions of the drum groove 41 are formed of increasing diameters as shown in Fig. 2^a as indicated at 41^a. Thus as the table approaches one end of its movement and one of the cables moves outwardly toward one end of the drum encountering the convolutions of increasing diameter, the slack is taken up automatically.

One end of the drum shaft 42 projects rearwardly from the bed 15, and has a worm wheel 45 secured thereon. A worm 46 meshing with the wheel 45 is fixed on a shaft 47 driven by an electric motor 48 on the pedestal 17. Suitable reversing dogs 49 mounted in spaced relation on the front flange 25 of the table 19 for adjustment along a T-slot 50 are adapted to coat alternately with a switch element 51 on the base 15 to control the direction of rotation of the motor 48, and thereby to control the reciprocation of the table.

The sheet A may be secured in position on the table 19 in various ways. Thus, suction may be employed. Preferably, one end of the sheet A is fastened or held to the table 19 while the other end remains free, the belt B being operated in a direction such that the abrading action will maintain the sheet taut at all times. While clamps or any suitable holding means may be employed, two hooks 52 (Figs. 5, 7 and 8) are provided in the present instance for securing the right end of the sheet B to the table 19, and the abrasive belt B is driven to exert a pull to the left. Each hook 52 has a clip 53 on one end fitting over a flange 54 on the right end of the table 19, and the hook proper on the other end adapted to be inserted through a slit 55 in the adjacent end of the sheet A.

To provide for vertical adjustment of the tool head 20, the column 16 is formed on the front with two parallel spaced vertical guideways 56 (Fig. 12). The head 20 comprises a generally flat vertical frame 57 which is formed along its rear vertical edge with two parallel spaced guides 58 slidably secured in the guideways 56 by gib plates 59. Formed on the rear of the frame 57 between the ways 56 and adjacent the lower end is a bracket 60 (Figs. 9 and 10) which projects into the column 16, and which has a laterally extend-

ing arm 61 on its underside. A nut 62 is fixed in the free end of the arm 61, and is in threaded engagement with a rotary vertical feed screw 63. The upper end of the screw 63 extends into and terminates in a gear housing 64 mounted in one side wall of the column 16. A bearing 65 in the lower wall of the housing 64 for the screw 63 serves to hold the latter against endwise motion. Fixed on the screw 63 within the housing 64 is a worm wheel 66 in mesh with a worm 67 on a transverse shaft 68 driven by an electric hoist motor 69. The shaft 68 is journaled in a housing 70 mounted on the exterior of the column 16 and enclosing the housing 64 and the motor 69, and extends to the front of the head frame 57 where it is provided with a hand wheel 71. It will be evident that the head 20 may be adjusted vertically by rotating the worm shaft 68 either by power from the motor 69 or manually by means of the hand wheel 71. The operation of the motor 69 may be controlled by a push button switch 72 mounted on the front of the bed 15.

The rollers 21, 22 and 22^a are mounted horizontally in substantially parallel spaced relation on the frame 57. The abrasive belt B runs over these rollers and about the frame 57. Power means for driving the belt B may be connected to any one of the rollers, but preferably is connected to the lower roller 21 so as to avoid objectionable tension on the intermediate flights of the belt.

The lower drive roller 21 is fixed on a horizontal supporting shaft 73 with tapered ends 74 and 75, and is located immediately beneath the head frame 57. In its preferred form, the roller 21 is provided with a peripheral layer 76 of a yieldable material, such for example as fabric, to compensate for irregularities in the sheet A, and thereby to enable all parts of the surface to be finished. A sleeve 77 is secured by means of a nut 78 on the tapered forward end 74 of the shaft 73, and is rotatably mounted in a ball bearing 79 in an oscillatory depending bearing bracket 80. The upper end of the bracket 80 is keyed to a rock shaft 81 extending through the frame 57 into the column 16, and slidably journaled in bearings 82 and 83 respectively in the front of the frame and the bracket 60. An upstanding pin 84 on the upper end of the bracket 80 is adapted to enter a slot 85 formed in an overlying portion of the frame 57 upon rearward movement of the shaft 81 to lock the bracket in vertical position. Fixed on the rear end of the shaft 81 within the column 16 is a suitable counterweight 86 which is normally in an ineffective vertical position, but which is adapted to facilitate swinging the bracket 80 sidewise when the pin 84 is out of the slot 85 and after the bracket 80 has been shifted axially beyond the end of the spindle.

The rear tapered end 75 of the shaft 73 is adapted to be removably inserted into a conical socket 87 formed in the adjacent end of an axially aligned drive shaft 88. A tie-bolt 89 (Fig. 9) extending axially through the shaft 88 serves to connect the shafts 73 and 88 automatically for joint rotation when the shaft end 75 is inserted into the socket 87. The shaft 88 is journaled in spaced bearings 90 in the bracket 60, and extends rearwardly into the column 16. Fixed on the rear end of the shaft 88 is a pulley 91 which is connected by a V-belt 92 to an electric drive motor 93 (Fig. 2) mounted on the pedestal 18. The belt 92 permits any vertical adjustment of the head 20 that may be necessary. The foregoing construction permits ready and convenient re-

removal of the pressure roller 21. Thus, by removing the nut 78 and sliding the rock shaft 81 forwardly to withdraw the bearing from the shaft end 74, the roller 21 and its spindle 73 may be withdrawn.

The upper roller 22, which preferably is similar in construction to the roller 21, extends closely along the top of the frame 57, and is rotatable on shafts 94 fixed in the right hand block 95 10 as shown in Fig. 9.

Either or both ends of the upper roller 22 may be adjusted vertically to accommodate belts B of different lengths or varying in length along their width. Thus, if one edge of the belt B 15 should be somewhat greater in length than the other edge, the roller 22 would be vertically inclined. To permit vertical and angular adjustment of the roller 22, the bearing blocks 95 are pivotally mounted respectively on two transverse pins 96 in two bifurcated heads 97. These heads are fixed on the upper ends of two cylindrical plungers 98 which are slidable in two cylinders 99 rigid with the front and rear of the head frame 57.

25 The plungers 98 are each formed with an axial bore 100 open and enlarged at the lower end. Seated in the enlarged portions of the bores 100 are two fixed nuts 101 in threaded engagement with two vertical adjusting screws 102 and 30 103. The rear screw 102 has a reduced shaft extension 104 extending through a bushing 105 into a gear housing 106 formed in the rear side of the frame 57. A collar 107 on the shaft extension 104 bears against an end thrust ball bearing 35 108 seated on the bushing 105. Fixed on the inner end of the shaft extension 104 is a bevel gear 109 which meshes with a similar gear 110 on the rear end of a horizontal shaft 111 extending through a bearing 112 into the housing 106. The 40 collar 107 and the gear 109 serve to anchor the screw 102 against endwise motion in the frame 57.

The horizontal shaft 111 extends forwardly through a bearing 113 into a gear housing 114 formed in the front portion of the frame 57. The 45 front of the housing 114 is open, and is adapted to be closed by a removable cover plate 115. A reduced extension 116 on the shaft 111 within the housing 114 is journaled in a bearing 117 in the cover plate 115. Fixed on the shaft 111 is a gear 50 118 which meshes with an elongated pinion 119 on a parallel shaft 120. The rear end of the shaft 120 is slidably and rotatably supported in the inner wall of the housing 114. The front end of the shaft 120 extends into and is splined for longitudinal movement in a tubular aligned shaft 121 journaled in a bearing 122 in the cover plate 115. A hand wheel 123 is fixed on the outer end of the shaft 121. Thus, the screw 102 may be actuated selectively in either direction to adjust the rear 60 end of the upper roller 22 vertically by rotating the hand wheel 123.

The front screw 103 similarly has a reduced shaft extension 124 extending through a bushing 125 into the housing 114. A collar 126 on the 65 shaft extension 124 bears against an end thrust ball bearing 127 seated on the bushing 125. A bevel gear 128 is fixed on the shaft extension 124 and with the collar 126 serves to anchor the screw 128 against endwise movement in the frame 57. The bevel gear 128 meshes with axially opposed 70 bevel gears 129 and 130 freely rotatable on the shaft extension 116 and rigid respectively with gears 131 and 132. Two spaced pinions 133 and 134 rigid with the shaft 120 are selectively movable respectively into mesh with the gears 131

and 132 upon shifting of the shaft 120 in opposite directions. To afford means for adjusting the shaft 120 axially, it is provided with an annular peripheral groove 135 receiving a pin 136 on a manually adjustable crank arm 137.

5 Rotation of the hand wheel 123 will always effect actuation of the rear screw 102. If the pinions 133 and 134 are located between the gears 131 and 132 no rotation of the screw 103 will result. However, the front screw 103 may be rotated in the same direction as or oppositely to that of the screw 102 by adjusting the pinion 133 into mesh with the gear 131 or the pinion 134 into mesh with the gear 132. The adjusting means is therefore capable of positioning the upper 15 roller 22 in any desired vertical and angular position to tension the belt B uniformly across its width.

The other roller 22^a (Figs. 11 and 13) is adjustably mounted across one side of the head 20 frame 57 and vertically between the lower and upper rollers 21 and 22. This intermediate idler roller preferably is the same in construction as the other rollers, and is freely rotatable on a generally horizontal shaft 138 fixed at its 25 opposite ends in spaced bearing arms 139 and 140. These arms are keyed to a transverse horizontal rock shaft 141 extending through and journaled at opposite ends in bearings 142 formed in the front and rear walls of the frame 57. The 30 rear end of the shaft 141 extends into the column 16, and has keyed thereto a sleeve 143 formed with two oppositely extending horizontal arms 144 and 145. A counterweight 146 is pivotally suspended from the free end of the arm 144, 35 and is adapted to act in a direction tending to swing the intermediate roller 22^a outwardly to tighten the belt B. The free end of the other arm 145 is pivotally connected to a vertical depending non-rotatable adjusting screw 147 which 40 is in threaded engagement at its lower end with a nut 148 rotatably anchored in a bearing bracket 149 on the frame 57. A bevel gear 150 is fixed on the nut 148, and meshes with a bevel gear 151 keyed to the rear end of a transverse shaft 152. 45 The forward end of the shaft 152 is supported by a bearing 153 on the front of the frame 57, and is provided with a hand lever 154. Thus, the idler roller 22^a may be swung by actuating the lever 154. While it is desirable to provide for 50 angular adjustment of the arms 140 as described, it is to be understood that the arms may be made rigid with the frame 57, and that adjustment of the upper roller 22 may be solely relied upon to tension the belt B.

If the upper roller 22 is slightly inclined to compensate for unevenness in the length of the belt B along its width, the belt is likely to creep. Hence, provision is made for adjusting the idler roller 22^a angularly so that it may be inclined oppositely to the upper roller 22 to counteract this creeping tendency. In the preferred form, the rear end of the shaft 138 is rotatably and slidably mounted in a block 155 pivotally mounted in a bifurcation 156 on the free end of the rear bearing arm 139. The forward end of the shaft 138 is clamped by means of a set screw 157 in a block 158 freely slidable in a substantially vertical guideway 159 formed in the free end of the front bearing arm 140. A pivot pin 160 is freely rotatable in the block 158 and extends transversely of the shaft 138 and the guideway 159. One end of the pin 160 is flattened to form a key 161 which projects slidably into a substantially vertical groove 162 extending along one side of the guide- 75

way 159, and which constrains the pin to move rectilinearly. A vertical adjusting screw 163 extends diametrically through the pin 160 and is rotatably anchored thereto. The upper end of the screw 163 extends loosely through the block 158 and the shaft 138 and is threaded into the arm 140. A hand wheel 164 is fixed on the lower end of the screw 163. Upon rotation of the screw 163, the pin 160 will be adjusted along the guide-way 162, and the block 158 will be pivoted about the pin. As a result, the idler roller 22^a will be tilted in a generally vertical direction about the pivot for the block 155.

In operation, the upper roller 22 is adjusted vertically and angularly if necessary to place the belt B under a uniform tension. If the upper roller is vertically inclined, the aligning roller 22^a is adjusted into a suitably inclined position to prevent the belt from creeping. A flexible sheet A of metal to be finished is placed upon the table 19 and is fastened at the right end by the clamps 52. Then, the head 20 is adjusted vertically to adapt the belt B to the thickness of the sheet A and the desired depth of cut. The table 19 is now reciprocated from left to right while the belt B is driven in a clockwise direction to hold the sheet A taut. As the sheet A is advanced past the belt B, the upper surface is provided with a smooth and uniform finish.

The sheet A is presented in a fully curved condition to the belt B. As a result, buckling of the sheet on the table is effectually reduced and the sheet is presented to the belt in substantially flat condition. The machine is simple and inexpensive in construction, and efficient and accurate in operation.

We claim as our invention:

1. A machine for surfacing thin work sheets comprising, in combination, an elongated horizontal bed having parallel longitudinal ways on the top, each way consisting of two straight sections inclined downwardly and oppositely toward the ends of said bed, an elongated table supported at opposite ends on the opposite end sections of said ways and being vertically spaced from said ways at all intermediate points, means for reciprocating said table longitudinally of said bed, a horizontal surfacing tool extending perpendicularly across said table, and means for actuating said tool, the top of said table having a longitudinally curved surface convex upwardly and adapted to support the work sheet and in the course of said reciprocation to present all points along said sheet progressively to said tool at a predetermined height.

2. A surfacing machine comprising, in combination, an elongated horizontal bed, a work support mounted for longitudinal translation on said bed, a surfacing tool mounted in position over said support and extending transversely thereof, said support having a longitudinally curved surface on which a work sheet is adapted to be mounted in fixed position and which is adapted to present the upper surface of the sheet in a fully and convexly curved condition to said tool, and means for translating said support.

3. A surfacing machine comprising, in combination, an elongated horizontal bed having longitudinal guides, a work support mounted for longitudinal reciprocation on said guides along said bed, a surfacing tool mounted in position over said support and extending transversely thereof, said support having a longitudinally curved surface convex upwardly on which a work sheet is adapted to be mounted in fixed position

and which is adapted to present the sheet in a curved condition to said tool, means for securing the work sheet in fixed position on said support, and means for reciprocating said support, said guides serving to rock said support to present successive points along said sheet progressively to said tool at a predetermined height.

4. A surfacing machine comprising, in combination, an elongated horizontal bed, longitudinal guide means on said bed, an elongated work support mounted on said guide means for translation longitudinally of said bed, a surfacing tool mounted in position over said support and extending transversely thereof, said support having a surface curved longitudinally of said bed on which a work sheet is adapted to be mounted in fixed position and which is adapted to present the work sheet in a fully curved condition to said tool, means for anchoring the sheet at one end, said tool acting in a direction to hold the sheet taut, and means for translating said support, said guide means adjusting said support in the course of its translation to compensate for the curvature of said surface, whereby all points along said sheet are presented successively at the same height to said tool.

5. A surfacing machine comprising, in combination, an elongated horizontal bed, longitudinal guide means on said bed, an elongated work support mounted on said guide means for translation longitudinally of said bed, a surfacing tool mounted in position over said support and extending transversely thereof, said support having a surface curved longitudinally of said bed on which a work sheet is adapted to be mounted in fixed position and which is adapted to present the work sheet in a convexly curved condition to said tool, and means for translating said support, said guide means adjusting said support in the course of its translation to compensate for the curvature of said surface, whereby all points along said sheet are presented successively at the same height to said tool.

6. A machine for surfacing thin work sheets comprising, in combination, an elongated horizontal bed having parallel generally longitudinal ways on the top, an elongated table supported on said ways, the top of said table having a longitudinally curved surface convex upwardly and adapted to support the work sheet in a fixed and fully curved condition, a horizontal surfacing tool extending across said table, means for operating said tool, and means for reciprocating said table along said ways, said ways acting to guide said table in a curved path to present all points along said sheet progressively to said tool at a predetermined height.

7. An abrading or polishing machine comprising, in combination, a horizontal bed having an upstanding column, a work support mounted for generally horizontal movement on said bed, a tool head having a frame mounted for vertical adjustment on said column, a horizontal pressure roller mounted on the underside of said frame and extending transversely across said support, a tension roller generally parallel to said pressure roller and mounted in the top of said frame for vertical and angular adjustment, two spaced arms on said frame, a bearing block pivotally mounted in one of said arms, an adjusting slide mounted in the other of said arms, a bearing block pivotally mounted in said slide, an aligning roller generally parallel to said first mentioned rollers and having a shaft supported by said blocks, means for adjusting said slide to adjust the angular position of

said aligning roller relative to said tension roller, and an endless tool belt running over said rollers. 8. An abrading machine comprising, in combination, a horizontal bed having an upstanding 5 column, a work support mounted for generally horizontal movement on said bed, a tool head having a frame mounted for vertical adjustment on said column, a horizontal pressure roller mounted on said frame and extending transversely across said support, a tension roller generally parallel to said pressure roller and mounted in said frame for linear and angular adjustment in an axial plane through said pressure roller, an 10 aligning roller generally parallel to said first mentioned rollers and mounted on said frame for angular adjustment, said tension and aligning rollers being adapted to be adjusted into oppositely inclined angular positions, and an endless tool belt running over said rollers.

20 9. An abrading or polishing machine comprising, in combination, a horizontal bed having an upstanding column, a work support mounted for generally horizontal movement on said bed, a tool head having a frame mounted for vertical adjustment on said column, a horizontal pressure roller mounted on the underside of said frame and extending transversely across said support, a tension roller generally parallel to said pressure roller and mounted in the top of said frame for 25 vertical and angular adjustment, an aligning roller generally parallel to said first mentioned rollers and mounted on said frame for lateral swinging adjustment and for angular adjustment, said tension and aligning rollers being adapted 30 to be adjusted into oppositely inclined angular positions, and an endless belt running over said rollers and about said frame.

10. A machine of the character described comprising, in combination, a tool support and a work support mounted for relative translation, a fixed bearing and a movable bearing on said tool support, said movable bearing being laterally adjustable into and out of alignment with said fixed bearing and being axially adjustable toward 45 and from said fixed bearing, a tool element having a shaft removably secured for rotation at one end in said movable bearing, a drive member journaled in said fixed bearing, the other end of said shaft being adapted for an interfitting driving 50 connection with said drive member, and means for locking said movable bearing in position to maintain said connection.

11. A machine of the character described comprising, in combination, a horizontal bed having 55 an upstanding column, a work support on said bed, a frame mounted on said column over said support, a drive shaft journaled in said frame and having a socket in one end, a rock shaft parallel to said drive shaft and slidably and rotatably 60 mounted in said frame, a counterweight fixed on said rock shaft, a bearing bracket secured to said rock shaft and having a rotatable socket adapted to be swung about said rock shaft into and out of axial alignment with said first mentioned 65 socket and to be adjusted axially toward and from said first mentioned socket, a pressure roller having a supporting shaft, means for removably securing one end of said supporting shaft in said rotatable socket, said bracket and said roller being adjustable to insert the other end of said supporting shaft into said first mentioned socket, interfitting means for connecting said supporting shaft to said drive shaft, and means for locking 70 said bracket in position.

75 12. An abrading or polishing machine comprising-

ing, in combination, a work support and a generally vertical tool support mounted for relative translation, two spaced rollers mounted in a common axial plane on said tool support, an endless tool belt running over said rollers, the lower of said rollers being a pressure roller for presenting said belt to said work support and being rotatably mounted in fixed position on said tool support, the upper of said rollers having a rotatable mounting angularly adjustable at each end in said plane, means for adjusting one end of said upper roller in said plane toward and from said pressure roller, and means for adjusting the other end of said upper roller in said plane toward and from said pressure roller, whereby said rollers may be disposed in different parallel spaced positions, and in different and reversible angular relations in said plane.

13. An abrading or polishing machine comprising, in combination, a bed having an upstanding column, a work support mounted for generally horizontal movement on said bed, a tool head having a generally flat vertical frame mounted for vertical adjustment on said column, a horizontal pressure roller mounted in the lower end of said frame and extending transversely across said support, the upper end of said frame having two parallel vertical cylindrical guides, two guide members vertically adjustable in said guides and carrying pivotal bearing blocks at 20 their upper ends, a tension roller journaled at opposite ends in said blocks, two adjusting screws in threaded engagement with said guide members, drive means operatively connected to one of said screws for adjusting the latter in either 25 direction, and gear means including a reversible clutch for connecting said drive means to the other of said screws to adjust the latter in the same direction as or oppositely to said first mentioned screw, and an endless tool belt running 30 over said rollers.

14. A surfacing machine comprising, in combination, a bed having an upstanding column, a work support mounted for generally horizontal movement on said bed, a tool head mounted for vertical adjustment on said column, a horizontal pressure roller mounted on said head and extending transversely across said support, two parallel vertical guides on said head, two guide members vertically adjustable in said guides and carrying 45 pivotal bearing blocks, a tension roller journaled at opposite ends in said blocks, two adjusting screws in threaded engagement with said guide members, drive means operatively connected to one of said screws for adjusting the latter in either 50 direction, and means including a reversible clutch for connecting said drive means to the other of said screws for adjusting the latter in the same direction as or oppositely to said first mentioned screw, and an endless tool belt running 55 over said rollers.

15. A surfacing machine comprising, in combination, an elongated horizontal bed, a work support mounted for longitudinal translation on said bed, a surfacing tool mounted in position over said support and extending transversely thereof, said support having a longitudinally curved surface on which a work sheet is adapted to be mounted in fixed position and which is adapted to present the upper surface of the sheet in a fully 65 curved condition to said tool, and being formed with internal cooling passages for dissipating heat from the sheet, means for adjusting the 70 finishing tool vertically to adapt same to the 75

thickness of the sheet, and means for translating said support.

16. A machine of the character described comprising, in combination, a bed, a table mounted for reciprocation on said bed, a transverse drive drum on said bed, and two cables anchored to and wound oppositely on said drum and attached at their other ends respectively to opposite ends of said table, the longitudinal sections of said drum being of different diameters and each cable leaving the drum surface on an increased diameter when the cable approaches its limit position in unwinding from the drum.

17. A machine for surfacing thin work sheets comprising, in combination, an elongated horizontal bed having parallel longitudinal ways on the top, each way consisting of two straight sections inclined downwardly and oppositely toward the ends of said bed, an elongated table supported at opposite ends on the opposite end sections of said ways and being vertically spaced from said ways intermediate its ends, means for recipro-

cating said table longitudinally of said bed, a surfacing tool operatively mounted over said table, and means for actuating said tool.

18. An abrading or polishing machine comprising, in combination, a work support and a tool support mounted for relative translation, two spaced rollers mounted in a common axial plane on said tool support, an endless tool belt running over said rollers, one of said rollers being a pressure roller for presenting said belt to said work support, means for adjusting said rollers at one end relatively toward and from each other, means for adjusting said rollers at the other end relatively toward and from each other, and means having a common actuator and operable selectively to actuate one or both of said two first mentioned means in independent directions, whereby said rollers may be disposed in different parallel spaced positions and in different angular relations.

CHARLES JOHNSON.
JOSEPH O. OLSEN.
